[57] CLAIM

The ornamental design for a modular block, as shown and described.

DESCRIPTION

FIG. 1 is a front perspective view of a modular block showing our new design;

FIG. 2 is a top plan view thereof;

FIG. 3 is a bottom plan view thereof;

FIG. 4 is a side elevational view thereof, the other side view being a mirror copy of this view;

FIG. 5 is a front elevational view thereof; and,

FIG. 6 is a rear elevational view thereof.

FIG. 1

FIG. 2

FIG. 3

FIG. 4

FIG. 5

FIG. 6
